UNITED STATES PATENT OFFICE.

FRANK J. LYNCH, OF HILLSIDE, NEW JERSEY, ASSIGNOR TO THE SUN TUBE CORPORATION, OF HILLSIDE, NEW JERSEY, A CORPORATION OF NEW JERSEY.

CONVEYER CHAIN.

Application filed May 1, 1928. Serial No. 274,967.

This invention relates to conveyer chains, and has for an object to provide an improved construction wherein article-supporting members are connected to a chain in such a manner 5 as to maintain the centers properly spaced.

Another object of the invention is to provide a conveyer chain wherein article-supporting members are provided and formed at their ends with projections acting as pintles 10 for certain makes of chain.

In the accompanying drawings—

Figure 1 is a fragmentary plan view of a conveyer chain disclosing an embodiment of the invention, certain parts being broken 15 away and better illustrating the construction; the chain being also shown in connection with tubes which are to be conveyed.

Figure 2 is an edge view of the chain shown in Figure 1.

Referring to the accompanying drawings by numeral, 1 indicates the chain as a whole, and 2 the article supports. These supports are adapted to receive any desired article, as for instance, tubes 3. The chain is adapted 20 particularly to be used on automatic or semi-automatic machines and is designed to cooperate with machines which automatically put the tubes 3 on the supports or carriers 2, and later take them off. For this reason, it is 25 desired that the supports or carriers 2 shall be always the same distance apart in order to coat with the automatic machinery just mentioned.

In order to secure this result, each of the 30 carriers or supports 2 is provided with a machined extension or end 4, a shoulder 5 and riveted end 6 formed on the reduced rear extension 7, the machined extension 4 being formed with a shoulder 7' so that when the 35 rear extension 7 is upset link member 1' may be clamped without pressing the shoulder 5 against link member 1''. Members 4, 6 and

7 form a pintle for chain 1, and consequently are always an exact distance from the adjacent pin 8.

As illustrated in Fig. 1, each ordinary pintle for the chain 1 is an extension of support or carrier 2. These extensions are machined, while the carrier is chucked in a turning machine, thus making the spacing very accurate, 50 so that coating automatic machinery may be readily used for applying or removing tubes 3.

The carriers 2 may of course be of any desired manufacture, but are preferably slightly longer than the tubes 3, provided the article supported will not interfere with the chain 1, and the chain may function in the usual manner as it passes over guiding and driving sprockets. Aside from the produced extension 4 and associated parts, the chain may be 55 of any desired or approved type, preferably formed substantially as shown in the drawings.

I claim:

A conveyer chain comprising a chain body and carrier pins, each of said carrier pins having machined reduced end portions acting as a pintle for said chain body, a shoulder at the end of said machined portion, said shoulder acting against one of the link members of the chain body, and a reduced portion having a shoulder acting against one of the link members of said chain, said reduced portion being upset at its outer end so as to act 75 as a rivet to hold the machined portion in place, and the entire pin carrier in a position substantially in the same plane as the chain body.

Signed at Hillside in the county of Union 80 and State of New Jersey this 27th day of April, A. D. 1928.

FRANK J. LYNCH.
